Primary Examiner — Ricky Pham(57) **CLAIM**

I claim the ornamental design for a utensil, as shown and described.

DESCRIPTION

FIG. 1 is a front perspective view of a utensil showing my new design, generally in the shape of a spoon;

FIG. 2 is a top plan view thereof;

FIG. 3 is a bottom plan view thereof;

FIG. 4 is a right side elevation view thereof;

FIG. 5 is a left side elevation view thereof;

FIG. 6 is a back elevation view thereof;

FIG. 7 is a front elevation view thereof;

FIG. 8 is a front perspective view of a utensil showing my new design, generally in the shape of a fork;

FIG. 9 is a top plan view of FIG. 8;

FIG. 10 is a bottom plan view of FIG. 8;

FIG. 11 is a right side elevation view of FIG. 8;

FIG. 12 is a left side elevation view of FIG. 8;

FIG. 13 is a back elevation view of FIG. 8; and,

FIG. 14 is a front elevation view of FIG. 8.

The broken lines shown in the drawings are for illustrative purposes only and form no part of the claimed design.
